No. 767,336.

PATENTED AUG. 9, 1904.

H. L. FERRIS.

WIRE STRETCHER.

APPLICATION FILED MAR. 18, 1904.

NO MODEL.

UNITED STATES PATENT OFFICE.

HENRY L. FERRIS, OF HARVARD, ILLINOIS, ASSIGNOR TO HUNT, HELM, FERRIS & COMPANY, OF HARVARD, ILLINOIS, A CORPORATION OF ILLINOIS.

WIRE-STRETCHER.

SPECIFICATION forming part of Letters Patent No. 767,336, dated August 9, 1904.

Application filed March 18, 1904. Serial No. 198,855. (No model.)

To all whom it may concern:

Be it known that I, HENRY L. FERRIS, a citizen of the United States of America, residing at Harvard, in the county of McHenry and 5 State of Illinois, have invented certain new and useful Improvements in Wire-Stretchers, of which the following is a specification.

My invention relates to certain new and useful improvements in wire-stretchers; and its 10 object is to produce a device of this class which shall have certain advantages which will appear more fully and at large in the course of this specification.

To this end my invention consists in certain 15 novel features of construction, which are clearly illustrated in the accompanying drawings and described in this specification.

In the aforesaid drawings, Figure 1 is a plan view of my improved wire-stretcher. Fig. 2 20 is a side elevation of one end of the wire-stretcher, on an enlarged scale. Fig. 3 is a front end elevation of the end of the wire-stretcher looking in the direction of the arrow in Fig. 2. Fig. 4 is a section in the line 25 4 4 of Fig. 1 looking in the direction of the arrow. Fig. 5 is an enlarged detail elevation of the sliding yoke; and Fig. 6 is an enlarged detail perspective of the same, partly broken away.

Referring to the drawings, A is a suitable ratchet-bar, having notches upon opposite sides. At the end of this bar A is a hook a, to which are secured the ends of a chain A', which is passed around a post or other support 35 to secure the end of the bar A in place.

Upon this ratchet-bar A is a sliding yoke or slide B, the construction of which is illustrated in Figs. 5 and 6. It will be seen that this slide consists of two parallel plates having 40

at their front and rear a slightly-greater width than the width of the ratchet-bar, these plates being connected at front and rear by suitable struts b. The side pieces of this slide are cut away near the forward ends to expose 45 the upper and lower notched surface of the ratchet-bar, as is clearly indicated in Fig. 1.

Upon the slide B are oppositely-extending gudgeons b', to which is pivoted a lever B',

composed in the preferred form of two straps of sheet metal secured together at their lower 50 ends and separated at their upper ends to straddle the slide. Between the ends of these straps are pivoted two bar-engaging dogs C on opposite sides of the bars A. On the forward end of the slide B is a laterally-extending gudgeon b'', and above this gudgeon is a laterally-extending jaw b'', in the preferred form having a flat lower surface and a curved upper surface. Upon the gudgeon b'' is pivoted a lever D, which has a flange d overhanging 55 the edge of the jaw b'' and a plurality of teeth d' arranged in a curve eccentric with respect to the gudgeon b'', the rear teeth being further removed from the center than the front, so that the lever is rotated counter-clockwise from a position seen in Fig. 1. The teeth approach the jaw b''.

On the front end of the rod A is a casting E. This casting has a portion e at right angles to the plane of the ratchet-bar A, this portion being normally vertical, an overhanging normally horizontal portion e', having a flared end e'', a downwardly-extending piece e'', and a normally horizontal gudgeon e'', all these parts being in the preferred form of construction 70 cast integral. Upon the gudgeon e'' is journaled a clamping member F, having at one end a hand-lever and at the other a toothed portion f, the teeth of which are arranged in an eccentric curve and adapted to swing toward 75 and coöperate with the overhanging portion e'' of the casting E when the clamping-lever F is rotated in a counter-clockwise direction from the position seen in Fig. 2. A spring F' holds this lever normally in engagement 80 with this overhanging portion.

The operation of my improved device will now be readily apparent. The device is attached to a post, as illustrated, and barbed or other wire is then passed through the clamp 90 at the forward end of the device and secured between the teeth on the clamping-lever D and the lower end of the jaw b'', as indicated in Fig. 1. When in use, the ratchet-bar A occupies a horizontal position, and the weight of 95 the forward end thereof is supported by the

overhanging horizontal portion e' of the casting E, which hangs upon the wire. After the wire is secured in the clamp on the slide the operating-lever B' is worked back and forth, 5 and the slide moves back on the rod in the ordinary way, the wire running through the clamp at the forward end of the rod by rotating the clamping-lever F against the force of the spring F'. When, however, the slide 10 has moved to the rear end of the rod A and it is desired to pull in more wire, the clamping-lever D is released by hand, and the wire will be held taut by the forward clamp, the spring holding the clamping-lever in engagement 15 with the wire. The operation of pulling up the wire can then be repeated as often as desired. A particular advantage of my improved construction consists in the fact that the clamp at the forward end of the rod is 20 always in position to engage with the wire to prevent any backward movement of the same, and yet does not interfere with the forward movement thereof, and in the further fact that this clamp hangs upon the wire and causes the 25 wire to furnish a support for the forward end of the device. The construction of the slide having the integral wire-clamping jaw b' is an additional improvement and overcomes the use of loosely-connected clamping-jaws, which are

a constant source of annoyance. The present 30 construction is extremely simple and effective in its operation.

I realize that considerable variation is possible in the details of this construction without departing from the spirit of the invention, 35 and I therefore do not intend to limit myself to the specific form herein shown and described.

I claim as new and desire to secure by Letters Patent—

In a device of the class described, the combination with a bar and means on the rear end of the bar for connecting the same to a post or other support, leaving the front end of the bar free to move, of a slide moving thereon, 45 suitable means for advancing the same along the bar, a clamp carried by said slide and a guiding device and wire-clamp on the forward end of the bar.

In witness whereof I have signed the above 50 application for Letters Patent, at Harvard, in the county of McHenry and State of Illinois, this 10th day of March, A. D. 1904.

HENRY L. FERRIS.
